UNITED STATES PATENT OFFICE

FREDERICK A. HART, OF NEW BRITAIN, CONNECTICUT, ASSIGNOR TO REMINGTON TYPEWRITER COMPANY, OF ILION, NEW YORK, A CORPORATION OF NEW YORK

TYPEWRITING MACHINE

Original application filed October 22, 1926, Serial No. 143,382, now Patent No. 1,825,148. Divided and this application filed December 1, 1927. Serial No. 236,984.

My invention relates to typewriting or like machines and to so-called billing mechanism for such machines. The present invention involves improvements on the construction disclosed in my Patent No. 1,650,351, dated November 22, 1927, and is a division of my application, Serial No. 143,382 filed October 22, 1926, now Patent No. 1,825,148, dated Sept. 29, 1931.

The object of the present invention, generally stated, is to improve my prior patented construction and to facilitate the handling and control of work sheets used therein. More specifically stated, the objects of the present invention are as follows:

(1st) To provide means for automatically locking the paper feed rollers which coact with the register sheet in ineffective position;

(2nd) To provide an improved manner of mounting the set of feed rollers which coact with the register sheet;

(3rd) To provide means for supporting the ledger sheet in a manner which will more readily facilitate the introduction of a comparatively thin bill or statement sheet;

(4th) To provide adjustable means for determining the normal position of the double deflector; and

(5th) To provide an improved side edge gaging means on the spindle or shaft for the feed rollers of the register sheet.

To the above and other ends which will hereinafter appear, my invention consists in the features of construction, arrangements of parts and combinations of devices set forth in the following description and particularly pointed out in the appended claims.

In the accompanying drawings wherein like reference characters designate corresponding parts in the different views,

Fig. 1 is an enlarged, detail, fragmentary side elevation of a portion of the so-called Remington "front feed" machine, with parts omitted and parts broken away.

Fig. 2 is a detail, fragmentary, top plan view of the same, with parts omitted and parts broken away.

Fig. 3 is a detail, fragmentary, front ele-

vation of one of the adjusting cams and some of the associated parts.

Fig. 4 is a detail perspective view of the double deflector and some of the devices associated therewith.

Fig. 5 is an enlarged, detail, transverse sectional view showing the means for adjustably supporting the double deflector in normal position, the section being taken on the line 5-5 of Fig. 2 and looking in the direction of the arrows at said line.

Fig. 6 is an enlarged, detail fragmentary sectional view of the left-hand end of the spindle for supporting the top feed rollers, together with the associated bearing for this end of the spindle; the section being taken on the line 6-6 of Fig. 1 and looking in the direction of the arrows at said line.

Fig. 7 is an enlarged, detail, transverse sectional view of the same taken on the line 7-7 of Fig. 6 and looking in the direction of the arrows at said line.

Fig. 8 is an enlarged, detail, transverse sectional view showing a portion of the double deflector and the manner in which it co-acts with various work sheets.

Fig. 9 is a detail, fragmentary, front elevation showing the spring for the double deflector and some of the associated parts.

My invention is shown in the present instance embodied in a Remington "front feed bookkeeping machine", but I have only shown so much of said machine as is necessary to illustrate the invention in its inclusion therein. It should be understood, however, that the invention is not restricted to embodiment in said machine, but is of general application wherever found available.

As in the machines hereinbefore referred to the present machine is capable of a wide range of uses in connection with various so-called billing operations and the like, where two or more work sheets are to be correlated in the machine and printed at a single operation. However, I do not deem it necessary to describe specifically the many different forms of billing operations in which the machine may be used. It is sufficient for an understanding of the present invention to specifically describe one mode of billing that

may be successfully carried out with the aid of the present machine, and perhaps briefly refer to some of the various other methods in connection with which the machine may 5 be employed.

One method of using the machine, which will be specifically referred to, is its employment for simultaneously, or at one writing, making out a "statement", making corresponding entries on the ledger sheet carrying the account, and on a record or register sheet which receives the various entries written on all of the individual statement and ledger sheets. In the example referred to 10 the register sheet and its accompanying carbon sheet remain in the machine. Means are provided to enable the ledger sheet and its accompanying carbon sheet to be quickly introduced and properly positioned to receive 15 the requisite entries without disturbing the previously introduced register sheet and its companion carbon sheet. Means also are provided for then quickly entering a statement sheet into the machine in front of the 20 platen and accurately positioning it in proper correlation with the previously introduced ledger sheet and the printing line. The entries may then be made on the statement sheet, and these will be transferred through the interposed carbon sheets to the ledger and register sheets. If desired, additional entries 25 may be made on the ledger sheet which are not to appear on the statement or register sheet. The statement and ledger sheets are then rapidly withdrawn from the machine 30 without disturbing the register sheet and its companion carbon sheet and another ledger sheet and statement sheet may then be quickly introduced, as before, and so on.

40 A line spacing operation, effected by the return of the carriage after writing a statement and making the corresponding entry on the ledger and register sheets, advances the register sheet in position to receive the 45 manifold copy of the next entry on the register sheet.

With the foregoing general explanation of the purpose and operation, I will proceed to describe the invention as it is embodied, in 50 the present instance, in said hereinbefore mentioned Remington machine.

The frame of the machine includes the usual top plate 1 supporting fixed guide rails 2. The carriage or truck comprises front and 55 rear guide or cross bars 3, united by end bars 4 and 5. The guide rails 2 and cross bars 3 are oppositely grooved to receive crossed anti-friction rollers 6, by which the carriage is supported in the usual manner 60 to travel from side to side of the machine over the top plate 1.

A cylindrical platen 7 is mounted in the usual manner in a platen frame comprising the rigidly connected end plates 8 and 9; 65 the platen frame being connected to the car-

riage by the usual shift links 10 and 11. In the present instance, however, I contemplate writing only with upper case characters and the platen is therefore preferably held in the upper case position. This may be readily done by screwing up the lowermost case-shift limiting screw-stops 12, thereby holding the platen shaft, or the buffer springs 13 which surround it, against the upper-case limiting stops 14. This brings the printing 70 line on the platen to a position where the uppermost types on the usual type bars will register therewith.

There are two curved paper deflectors 15 and 16 employed beneath the platen, one arranged above the other and maintained spaced apart by intermediate spacing members or blocks 17 and 18 located near the ends thereof. Generally speaking, these deflectors conform to the curvature of the platen or are substantially concentric therewith and extend substantially throughout the length of the platen. As thus constructed there are two separate channels provided, one of which is the open channel 19 between the two deflectors and which is bounded at its ends by separating members 17 and 18, either or both of which may constitute side guides or gages for cooperation with a work sheet or sheets introduced into the channel 19. The other separated channel 20 is provided between the under surface of the platen and the upper deflector 15. The forward edge of the deflector 16 terminates in advance of the forward edge of the deflector 15, and has a slight downward curve in cross section. The deflector 16 is continued up at the rear to form an upwardly and rearwardly extending paper table 21 which terminates at a considerable height above the platen. On the other hand, the deflector 15 terminates in the rear of the platen at a much lower point and below the top of the platen, where it is bent to form a loop 22 that loosely surrounds a rod 23 rigidly connected at its ends to the end plates 8 and 9 of the platen frame. In this manner the rigidly united deflectors 15 and 16 are mounted on the rod 23 and may have a slight pivotal movement thereon. A light wire spring 24 (Fig. 9) is connected by screws 25 and 26 to a cross bar 27 of the platen frame, the spring being anchored at one end on the screw 25 and coiled around the stem of the screw 26. The upper free end of the spring 24 is looped at 28, where it bears upward against the bottom of the deflector 16 and causes the forward edge portion of the deflector 15 normally to be lightly pressed against the platen, or against the interposed work sheet. In this manner the sheets introduced from the rear of the platen through the channel 20 will be held snugly against the platen, and the sheets introduced into the channel 19 will be prevented from entering the channel 20. By moving the upper end 100

of the paper table forward, the forward end portions of the deflectors may be moved downward a limited distance, thus carrying the forward contact edge of the deflector 15 away from the platen. Unless this contact of the deflector 15 with the platen is nicely regulated and controlled, there is apt to be an undue binding of said deflector on the platen, or on the register sheet, during the forward turning of the platen.

In accordance with the present invention I have provided adjustable means for determining the normal position of the double deflector on its pivot 23, and also for determining the limit of pivotal movement that said double deflector may receive away from normal position, which will now be described.

It will be seen that a cross bar or supporting rod 29 is connected at its ends to the end plates 8 and 9 of the platen frame, and is fixed thereto against turning movement. One or more sleeves 30 are mounted on this rod, two being shown in the present instance. Each sleeve is tapped transversely 25 throughout its diameter in two lines at right angles to each other, so as to provide a plurality of tapped openings 31. In the most convenient one of these openings is received a set screw 32 that is adapted to bear at its inner end against the supporting rod 29. Fixed to each sleeve 30 is a snail-cam 33, the curved contact edge of which is adapted to form a bearing against which the back of the paper table 21 is pressed by the spring 24, thus determining the normal position of the double deflector on its pivot and preventing the forward edge of the deflector 15 from bearing with undue force against the platen. By a turning adjustment of the cams 33 around their supporting rod, the position of the forward edge portion of the deflector 15 with reference to the platen may be nicely regulated, the screws 32 holding the cams in the positions to which they are adjusted.

In order to limit the pivotal motion of the double deflector in the opposite direction, I provide one or more additional adjustable snail-cams or stop devices 34 (see Fig. 3) to contact with the bottom of the deflector 16. The carriage of the Remington machine, as manufactured, has on its cross bar 27 a series of faced lugs 35 located near the ends of the bar, each of them being tapped fore-and-aft of the machine. In the present instance, I make use of two of these tapped openings to receive the stems of headed binding screws 36. On each of these screws is supported one of the cams 34. By slightly loosening each of the screws 36, the associated cam or stop 34 may receive a turning adjustment around the stem of its screw to bring the curved contact edge of the cam or stop closer to or further from the bottom of the deflector 16, and thus regulate the extent of releasing motion of the double deflector.

When the cams 34 are adjusted to the proper position, a tightening of the screws 36 will hold the cams with a binding action in such position.

In some instances it may be found desirable to hold the double deflector rigid in its adjusted position, with the forward end of the deflector 15 a definite predetermined distance from the platen. This may be readily attained with the aid of the cams 33 and 34. At this time the spring 24 is ineffective and if desired may be dispensed with. It will be seen, therefore, that the adjusting cams 33 and 34 are effective from either point of view or condition pointed out above.

It is intended at times to introduce rearwardly through the channel 19, first one comparatively heavy ledger sheet L (see Fig. 8), and then a comparatively thin or light statement sheet S. Ordinarily the tendency of the first introduced curved and relatively wider ledger sheet L is to spring or force itself towards the bottom of the channel 19, or against the upper side of the lower deflector 16. It follows, therefore, that the ledger sheet, under these conditions, will interfere to a certain extent with the subsequent rearward introduction of the statement sheet S between the previously introduced ledger sheet and the deflector 16. This difficulty is more pronounced when the statement sheet is relatively thin, or made from very light stock. In order to overcome this disadvantage I have provided, by the present invention, work sheet supporting means in the channel 19 for supporting the ledger sheet in an unobstructing position in said channel, where it will not interfere with the ready insertion and free passage through the channel of another work sheet, such as the statement sheet, as clearly indicated in Fig. 8. Such means in the present instance comprises a plurality of work-supporting members or ribs 37 carried by and projecting upward from the contact face of the deflector 16, in the channel 19. As shown, there are two of these supporting members or ribs 37, having a parallel arrangement and extending fore-and-aft of the machine through the channel 19 and terminating at 38 near the top of the paper table 21. The thickness of each rib 37 is preferably such that, within its field of operation in the channel 19, it occupies preferably about one-third of the space between the two deflectors 15 and 16. The ribs may be located at appropriate points longitudinally of the platen, and be properly spaced apart, in order to leave an intervening space between them.

Through this intervening space a work sheet S (Fig. 8) may pass free from obstruction through the channel 19, while another work sheet L is supported on the upper contact faces of the ribs 37. I prefer to mount the ribs so that they may be adjusted to different positions longitudinally of the platen,

in order that various widths of sheet S may be introduced between said ribs in the channel 19. Any suitable means may be employed for this purpose. In the present instance, I provide three parallel series of openings 39 in the deflector 16 and paper table 21 for each of the ribs. The different series of openings for each rib are spaced apart longitudinally of the platen about three-quarters of an inch. A series of screws 40 pass through a series of openings 39 and are received at their threaded ends in tapped openings in a companion rib, to detachably secure each rib in any one of the three positions to which it may be adjusted along the channel 19. It has been found in practice that the means described effectively overcome the difficulties pointed out above in successively introducing two work sheets in the channel 19.

In order to facilitate the backward introduction of the work sheets into the mouth of the channel 19 from in front of the platen, there is provided a guide, shield, or paper deflector 41 that is movable on the carriage from a substantially horizontally disposed ineffective position, shown in full lines in Fig. 1, to a downwardly and rearwardly inclined effective position, shown in dotted lines in said figure, and vice versa, as disclosed in my said patent. In order to receive these movements the deflector is constructed and mounted, in the present instance, in the specific manner disclosed in the application of S. L. Walsoe, filed September 2, 1926, Serial No. 133,228, now Patent No. 1,663,362, dated March 20, 1928.

As disclosed in my original application, Serial No. 143,382, now Patent No. 1,825,148, means are provided, which it is unnecessary to show for the purpose of the present invention, for automatically shifting the deflector 41 into and out of effective position. When this deflector is in the dotted line effective position, shown in Fig. 1, it overlaps and virtually forms a continuation of the deflector 16. In the movement of the deflector 41 to effective position it passes from a position where it is out of the path of the type bars to a position where it is in the path thereof and crosses the printing line, where it is effective in directing work sheets introduced rearward from in front of the platen downward into the open channel 19. From thence the sheets in question pass around and beneath the platen to the rear thereof.

The paper feeding mechanism embodied in the present construction includes a plurality of aligned paper feed rollers 42, arranged to coat with the top of the platen and with work sheets introduced from the rear of the platen through the channel 20. Said feed rollers 42 coat with said sheets after the latter have passed above and beyond the printing lines. The paper feed rollers 42, as shown in the present instance, are construct-

ed and mounted in the same general manner as in my said hereinbefore mentioned patent, except for changes in mounting the spindle on which said feed rollers turn, as will presently appear. Thus, the feed rollers are mounted for longitudinal adjustment along a supporting rod or spindle 43, supported at its ends by forwardly extending arms 44 that are pivoted on the supporting rod 29, hereinbefore referred to, which is secured at its ends to the platen frame. Springs 45 exert their force against the arms 44 and thus cause the feed rollers 42 to bear against the platen, or certain only of the work sheets thereon. By swinging the spindle or bail 43 upward and rearward the said feed rollers are released.

In accordance with my present invention I provide each of the arms 44 with an inwardly projecting bearing member 46, shown in detail in Figs. 6 and 7, in which the ends of the spindle 43 are loosely seated, as shown, the diameter of the bore of each bearing being greater than the diameter of the spindle. This is in order that there may be an equalization of pressure exerted from the individually acting springs 45 on opposite ends of the roller supporting spindle 43. Although it is desirable to thus loosely support the spindle 43 at opposite ends, so that said spindle may assume varying angular relations relatively to the axis of the platen as well as a parallel relation thereto, it also is desirable to prevent or limit the turning movement of the spindle in its bearings. This is preferred because, among other reasons, I mount side edge paper gages on the spindle 43, as will presently appear, and any material turning of the spindle which would displace said gages from effective position should be prevented. Therefore, I provide each end portion of the spindle with a cross pin 47 projecting from opposite sides of the spindle into slots 48 extending longitudinally of the companion bearing member 46 and through the walls thereof. The diameter of each pin is preferably slightly less than the width of the slot 48 in which it is received. This construction affords a slight relative pivotal movement between the arms 44 so that there may be an equalization of pressure of the springs 45 on the feed rollers 42 at the opposite ends of the spindle 43. The extent of this slight relative movement between the arms 44 is determined by the extent of lost motion of the pins 47 in their respective slots 48. When shifting the feed rollers 42 away from the platen the arms 44 will shift in unison when the slight extent of lost motion of the pins 47 in their slots 48 is taken up. Each bearing member 46 may be secured to its companion arm 44 by any suitable means. In the present instance each bearing member has a threaded extension or stud 49 which passes through an opening in the companion arm 130

44 and engages a nut 50 on the opposite side thereof.

In the present construction I have provided means for automatically locking the feed rollers 42 in ineffective position when they are thrown off. Referring more particularly to Fig. 1, it will be seen that the left-hand arm 44 carries an outwardly projecting headed pin 51. The stem of this pin passes through a curved slot 52 in a locking member or latch 53, pivoted on a headed pivot screw 54 threaded into a tapped opening in the end plate 8. The curvature of the slot 52, when the latch is in the full-line position, 10 is substantially concentric with the axis of the rod 29 on which the arms 44 turn. Extending at an angle to the slot 52 at the upper end thereof is a locking notch 55 that provides a locking shoulder 56. A leaf spring 57 is set 20 cured at one end by a screw 58 to the end plate 8, whereas the free end of said spring extends beneath a shoulder 59 on the latch 53. The force of this spring is exerted to shift the latch from the full to the dotted line position when the left-hand arm 44 is shifted to the dotted line position to release the feed rollers 42. The effect of this movement of the pivoted latch to the dotted line position is to bring the locking shoulder 56 beneath the pin 30 51, and positively hold the feed rollers 42 in the released position against the action of their springs 45. The latch 53 terminates at its upper end in a finger piece 60 by which the latch may be swung forward from the dotted to the full-line position, thereby releasing the pin 51 and enabling the feed rollers to be returned to normal position by their springs 45.

The automatically operating latching means described above leaves both hands of the operator free to adjust the register sheet and its accompanying carbon sheet when the feed rollers 42 are released.

In the present construction I have provided two independent side edge gages 61 and 62 which are mounted on the supporting rod or spindle 43, as shown in Figs. 1 and 2. Each gage is fixed on an independent hub or carrier 63, tapped to receive a set screw 64 by which it is held in any position to which it may be adjusted along the spindle 43 on which it is mounted. The gage 61 projects rearward from the supporting spindle for cooperation with the left-hand side edge of a work sheet introduced into the channel 20 from the rear of the platen, whereas the gage 62 extends forward from the spindle where it coats with the left-hand side edge of a work sheet introduced from in front of the platen in the channel 19. The spindle 43 being fixed against appreciable turning movement in the arms 44, will hold the gages from unduly turning around the axis of said spindle, when the gages are held in place by the set screws 64. Nevertheless, the gages

swing with the spindle when the latter is turned with the arms 44 around the axis of the supporting rod 29 to releasing position. It will be understood that by making the gages 61 and 62 relatively adjustable they may be adjusted one with reference to the other, as well as affording an adjustment of both of them to various points along the spindle while a given space between them is maintained. Moreover, it will be seen that each gage is reversible on the supporting spindle, so that the gages may be arranged with their hubs extending towards each other, as shown, or one extending outward to the left, or both extending inward to the right, or where the gages are to be brought in close relationship the hubs may extend away from each other, giving the closest possible arrangement of the plate-like gages 61, 62.

Aside from the side edge paper gages described above, it should be understood that suitable paper end stops, such, for example, as certain of the end stops described in the patent to C. E. Burns, No. 1,647,854, may be employed. However, since a specific description of such end stops is unnecessary to arrive at an understanding of the present invention, further reference thereto will be omitted.

In addition to the feed rollers 42 I provide two sets of marginal paper feed rollers, an inner set 65 and an outer set 66, arranged above the printing line, and means are employed for controlling said feed rollers and also for automatically controlling other devices in the machine as disclosed in my original application, Serial No. 143,382. A showing of such construction is, however, unnecessary in the present case and I have, therefore, merely diagrammatically represented such additional feed rollers in Fig. 1, as indicated at 65 and 66.

Assume that a register sheet R (Fig. 8) and its accompanying carbon sheet (not shown) have been introduced through the channel 20 and properly positioned with the leading edges thereof beneath their feed rollers 42. The operator then introduces a ledger sheet L from the front of the platen into the channel 19 and accurately positions said sheet. The outer feed rollers 66 are then caused to bear against the platen and against the margins of the previously introduced ledger sheet. The statement sheet S with an accompanying carbon sheet (the latter not being shown) may then be introduced from the front of the platen into the channel 19, and between a second inner set of feed rollers 65 and the platen, or the ledger sheet thereon. After the statement sheet and the accompanying carbon sheet have been properly adjusted, the said second set of feed rollers 65 is applied to the previously adjusted statement sheet S. The machine is then conditioned to proceed with the writing, and the

matter written will be produced on the statement sheet and through the carbon sheets on the ledger and register sheets.

After the "statement" is written as described, the operator simultaneously releases the two sets of feed rollers 65 and 66 permitting ready withdrawal of the statement sheet, the accompanying carbon sheet and the ledger sheet, at the same time conditioning the machine for new sheets to replace those withdrawn.

The register sheet, which is to take the accumulation of the various "statements" to be written, and a corresponding carbon sheet (having its effective face next to the register sheet) are, as indicated above, first introduced together from the rear of the platen through the channel 20, being positioned widthwise with the aid, say, of the side edge gage 61. The leading ends of the register and its carbon sheet are then introduced beneath the paper feed rollers 42 and the sheets are adjusted to proper position in a line feed direction. After initially positioning the register sheet in the manner indicated, no further attention need be paid to it in the successive introduction, writing and withdrawal of the different statement and ledger sheets. The register and associate carbon sheet having been initially positioned as indicated, a ledger sheet carrying the account of the "statement" to be written is introduced from in front of the platen through the channel 19, with the aid of the deflector 41 in the dotted line Fig. 1 position. The ledger sheet thus introduced may be properly positioned widthwise of the machine and the register sheet, with the aid of the side edge gage 62. The operator then positions the outer set of feed rollers 66 to clamp the ledger sheet against the platen and introduces the statement sheet S rearward through the channel 19 with the aid of the deflector 41. The second inner set of feed rollers 65 is then moved to effective position to clamp the statement sheet against the platen. The operator may now proceed to write the "statement" and simultaneously produce a manifold copy thereof in requisite positions on the ledger and register sheets. It will be understood that after writing each "statement" the carriage is automatically returned and the platen automatically line spaced, thereby spacing the platen to bring the register sheet in proper position to receive a manifold copy of the next "statement" written on the machine.

In substantially the same manner as that indicated above the machine may be employed as a check writing machine, at which time the sheet described above as a "register sheet" would constitute a manifold record of the checks written and may constitute a "pay roll sheet". In this event, however, no ledger sheet will be employed. The outer set of feed rollers 66 will be employed to coact with

the checks, leaving the inner set of feed rollers 65 ineffective.

Generally speaking, the sheet described above as a "register sheet", and which remains in the machine when the other sheets are removed and new ones inserted, may constitute a "register sheet", a "proof sheet", a "sales sheet", a "distributing sheet", or a "pay roll sheet", depending on the use of the machine for different purposes.

By the present invention I have provided a construction which has proved rapid of operation, highly efficient and reliable in use, which is compact and comparatively simple in construction and can be manufactured at comparatively small cost and be readily embodied in existing Remington machines without modifying, or materially modifying, the existing structural features of said machine.

Various changes may be made in the construction and certain parts thereof may be employed without others without departing from my invention as it is defined in the accompanying claims.

What I claim as new and desire to secure by Letters Patent, is:—

1. In a typewriting or like machine, the combination of a platen, a set of paper feed rollers coacting therewith, a spindle on which said feed rollers are mounted, arms mounted for independent pivotal movement and by which said spindle is supported, bearings on said arms in which the spindle is loosely seated to afford such independent pivotal movement of the arms and enable the spindle to assume different angular relations relatively to the axis of the platen, and means for limiting or preventing a turning movement of said spindle relatively to said arms without however affecting the ability of the spindle to assume different angular relations as specified.

2. In a typewriting or like machine, the combination of a platen, a set of paper feed rollers coacting therewith, a spindle on which said feed rollers are mounted, arms mounted for independent pivotal movement and by which said spindle is supported, bearings on said arms in which the spindle is loosely seated to afford such independent pivotal movement of the arms and enable the spindle to assume different angular relations relatively to the axis of the platen, means for limiting or preventing a turning movement of said spindle relatively to said arms without however affecting the ability of the spindle to assume different angular relations as specified, and a side edge paper gage carried by said spindle.

3. In a typewriting or like machine, the combination of a platen, a set of paper feed rollers coacting therewith, a spindle on which said feed rollers are mounted, arms mounted for independent pivotal move-

ment and by which said spindle is supported, bearings on said arms in which the spindle is loosely seated to afford such independent pivotal movement of the arms and enable the spindle to assume different angular relations relatively to the axis of the platen, means for limiting or preventing a turning movement of said spindle relatively to said arms without however affecting the ability of the spindle to assume different angular relations as specified, a side edge paper gage carried by said spindle, and means for affording an adjustment of said gage to different set positions along said spindle.

4. In a typewriting or like machine, the combination of a platen, a set of paper feed rollers coacting therewith, a spindle on which said feed rollers are mounted, arms mounted for independent pivotal movement and by which said spindle is supported, bearings on said arms in which the spindle is loosely seated to afford such independent pivotal movement of the arms and enable the spindle to assume different angular relations relatively to the axis of the platen, and means for limiting or preventing a turning movement of said spindle relatively to said arms, said means comprising a connection between said spindle and one of said bearings formed by a slot extending longitudinally of the spindle in one member, and a pin carried in the other member and projecting into said slot.

5. In a typewriting or like machine, the combination of a platen, a set of paper feed rollers coacting therewith, a spindle on which said feed rollers are mounted, arms mounted for independent pivotal movement and by which said spindle is supported, bearings on said arms in which the spindle is loosely seated to afford such independent pivotal movement of the arms and enable the spindle to assume different angular relations relatively to the axis of the platen, and means for limiting or preventing a turning movement of said spindle relatively to said arms, said means comprising a bearing slot through each spindle bearing member, and pins projecting from said spindle into said bearing slots, the bearing slots and pins being proportioned to afford a slight lost motion and permit a slight independent pivotal movement of said arms.

6. In a typewriting or like machine, the combination of a cylindrical platen, a pair of curved paper guiding devices between which a channel is provided and by which work sheets are guided through said channel around and beneath the platen, and separated combined work sheet guiding and supporting devices constantly maintained within said channel for supporting one work sheet in an unobstructing position therein and for passage therethrough while another narrower work sheet may be introduced and freely fed

through said channel between said combined guiding and supporting devices.

7. In a typewriting or like machine, the combination of a cylindrical platen, a pair of curved paper guiding devices between which a channel is provided and by which work sheets are guided through said channel around and beneath the platen, and separated work sheet supporting ribs extending from the contact face of one of said guiding devices and free from contact with the face of the other of said guiding device, said ribs being maintained spaced apart and curved to conform to the channel in which they are received.

8. In a typewriting or like machine, the combination of a cylindrical platen, a pair of curved paper guiding devices between which a channel is provided and by which work sheets are guided through said channel around and beneath the platen, and means for supporting and guiding a work sheet passing through said channel out of close relationship to one of said guiding devices thus providing an open passage for a second work sheet through said channel unobstructed by the first sheet.

9. In a typewriting or like machine, the combination of a cylindrical platen, two curved paper deflectors arranged one beneath the other below the platen and providing an intermediate channel between them through which work sheets may be introduced rearwardly from the front of the platen, and two curved work sheet supporting members contained within said channel and secured to the lower deflector and free from contact with the upper deflector, said supporting members being spaced apart to afford a free passage of a work sheet through the channel beneath another work sheet supported by said supporting members.

10. In a typewriting or like machine, the combination of a cylindrical platen, a pair of curved paper guiding devices between which a channel is provided and by which work sheets are guided through said channel around and beneath the platen, separated work sheet supporting devices constantly maintained within said channel for supporting one work sheet in an unobstructing position therein and for passage therethrough while another narrower work sheet may be introduced and freely fed through said channel between said supporting devices, and means for affording a relative adjustment between said work sheet supporting devices longitudinally of the platen so as to vary the space between them.

11. In a typewriting or like machine, the combination of a cylindrical platen, two curved paper deflectors arranged one beneath the other below the platen and providing an intermediate channel between them through which work sheets may be introduced rear-

wardly from the front of the platen, two combined work sheet guiding and supporting members having curved working faces contained within said channel, said members being secured to the lower deflector and free from contact with the upper deflector and spaced apart to afford a free passage of a work sheet through the channel beneath another work sheet supported by said supporting members, means that enable said work sheet supporting members to receive a relative adjustment longitudinally of the platen in order to vary the space between them, and a third paper deflector movable from an effective position where it crosses the printing line and aids in directing work sheets rearwardly into said channel.

12. In a typewriting machine, the combination of a carriage, a cylindrical platen carried thereby, a paper deflector which extends around beneath the platen and is mounted for movement towards and away from the platen, a spring which tends to force the deflector toward the platen, and adjustable means for limiting the extent of movement of the deflector towards the platen under the force exerted on the deflector by said spring.

13. In a typewriting or like machine, the combination of a carriage, a platen carried thereby, two curved paper deflectors arranged one above the other and extending beneath the platen, means for maintaining said deflectors spaced apart so that they with the platen will form two separated channels through which work sheets may pass, one of said channels being between the platen and the upper deflector, the other channel being between the two deflectors, said curved deflectors being pivotally supported on the carriage so that the forward edge of the upper deflector may bear lightly against the platen, a spring for moving the deflectors on their pivot towards the platen and adjustable means for limiting the pivotal movement of said paper deflectors towards the platen.

14. In a typewriting or like machine, the combination of a carriage, a platen carried thereby, two curved paper deflectors arranged one above the other and extending beneath the platen, means for maintaining said deflectors spaced apart so that they with the platen will form two separated channels through which work sheets may pass, one of said channels being between the platen and the upper deflector, the other channel being between the two deflectors, said curved deflectors being pivotally supported on the carriage so that the forward edge of the upper deflector may bear lightly against the platen, adjustable means for limiting the pivotal movement of said paper deflectors towards the platen, and independently adjustable means for limiting the pivotal movement of said paper deflectors away from the platen.

15. In a typewriting machine, the combination of a carriage, a cylindrical platen carried thereby, a paper deflector which extends around beneath the platen and is mounted for movement towards and away from the platen, a snail cam against which said deflector normally bears to limit the movement of the deflector towards the platen, and means for enabling said cam to receive a rotative adjustment to and for holding it in different set positions.

16. In a typewriting machine, the combination of a carriage, a cylindrical platen carried thereby, a paper deflector which extends around beneath the platen and is mounted for movement towards and away from the platen, a snail cam against which said deflector normally bears to limit the movement of the deflector towards the platen, means for enabling said cam to receive a rotative adjustment to and for holding it in different set positions, and a corresponding independently adjustably snail cam normally out of contact with said deflector and with which the deflector coacts to limit the motion of the deflector away from the platen.

17. In a typewriting or like machine, the combination of a cylindrical platen, a curved paper deflector beneath the platen, and a plurality of separated combined work sheet supporting and guiding devices projecting from the contact face of said deflector and having a contact face extending longitudinally in the direction of the line feed of the work sheets for supporting and guiding one work sheet off the contact face of the deflector and thus provide an unobstructed space between said combined supporting and guiding devices for the free passage of a second work sheet beneath the sheet supported by said combined devices.

18. In a typewriting or like machine, the combination of a cylindrical platen, a pair of curved paper guiding devices between which a channel is provided and by which work sheets are guided through said channel around and beneath the platen, separated work sheet supporting devices within said channel for supporting one work sheet in an unobstructing position therein and for passage therethrough while another narrower work sheet may be introduced and freely fed through said channel between said supporting devices, a set of feed rollers which coact with said narrower work sheet while the latter extends into said channel, a second set of feed rollers coacting with the wider sheet while the latter extends into said channel, and a third set of feed rollers out of cooperative relation with said relatively wide and narrow work sheets and coacting only with a register sheet introduced between the uppermost of said pair of guiding devices and the platen and effective to hold said register sheet against accidental displacement while

19. In a typewriting machine, the combination of a carriage, a cylindrical platen carried thereby, a paper deflector which extends around beneath the platen and is mounted for movement towards and away from the platen, a snail cam against which said deflector normally bears to limit the movement of the deflector towards the platen, and means for enabling said cam to receive a rotative adjustment to and for holding it in different set positions.

the other sheets are being inserted in or removed from said channel.

19. In a typewriting or like machine, the combination of a platen, a set of paper feed rollers, a spindle on which said feed rollers are mounted, and a plurality of side edge paper gages mounted on and adjustable along said spindle one independently of another to different set positions, each of said gages being reversible on said spindle, and provided with a hub off-set to one side thereof, the reversibility of the gages on the spindle enabling the gages to be brought close together on the spindle when desired.

15 Signed at the borough of Manhattan, city of New York, in the county of New York and State of New York this 30th day of November A. D. 1927.

FREDERICK A. HART.
